(57) **CLAIM**

The ornamental design for a portable camera for a monitor, as shown and described.

DESCRIPTION

FIG. 1 is a front, right side perspective view of a portable camera for a monitor showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of a portable camera for a monitor in a first configuration of use.

The broken lines indicate portions of the article that form no part of the claimed design. Additional broken lines in FIG. 8 indicate environment that forms no part of the claimed design.

1 Claim, 8 Drawing Sheets
